UNITED STATES PATENT OFFICE.

CLINTON H. LEGGETT, OF NEW YORK, N. Y.

BOTTLE FOR GLUE, &c.

SPECIFICATION forming part of Letters Patent No. 501,282, dated July 11, 1893.

Application filed January 24, 1893. Serial No. 459,536. (No model.)

To all whom it may concern:

Be it known that I, CLINTON H. LEGGETT, a citizen of the United States, and a resident of the city, county, and State of New York, have 5 invented certain new and useful Improvements in Bottles for Glue and Like Liquids, of which the following is a specification.

This invention relates to bottles or packages for glue, mucilage, and other adhesive 10 liquids, and is designed to provide an improved cork or closure for such bottles, preferably the class wherein the cork carries a brush for applying the contents of a bottle when used.

15 In its preferred form in carrying out my invention I provide a cork fitting the bottle and carrying a brush, the stem of which rises through the cork and is fixed in position therein, and I coat the cork and brush with 20 paraffine or a like material where exposed to contact with the contents of the bottle, and I fix a paper strap to the cork above this coating, the ends of which are pasted to the neck of the bottle to prevent the removal of the 25 cork, and the portion of which between the cork and pasted ends can be torn or cut to free the cork when it is to be withdrawn from the bottle, and I provide certain other improvements which will be hereinafter fully 30 set forth.

In the accompanying drawings, which illustrate certain adaptations of my invention, Figure 1 is a perspective view of a glue bottle and its closure constructed according to 35 the preferred form of my invention, the stopper retaining paper band being shown as severed at one side. Fig. 2 is a vertical mid-section thereof, and Fig. 3 is a side elevation of a modified construction of stopper, certain of the parts being in axial section.

40 Referring to the drawings let A indicate an ordinary glass bottle, as a glue bottle or mucilage bottle, B the contracted neck thereof, C the head thereof, and D the mouth thereof.

45 Let E represent the closure as a whole, F the cork or stopper thereof, entering the mouth D of the bottle, G the handle of the brush carried by the cork F, H the brush, and I the strap fixed to the cork for preventing its 50 removal from the bottle.

The bottle A may be of any suitable construction, and is originally filled with a quantity of glue, mucilage or other adhesive liquid J.

The closure E is constructed according to 55 the preferred form of my invention of a slightly conical perforated piece of cork F, fitting the tapering mouth D of the bottle. The perforation of this cork is lettered a in Fig. 2, and is disposed axially traversing the 60 cork F from top to bottom. Through this perforation a passes the handle G of the brush H, the handle being a snug fit with the middle portion b of the perforation a, and the cork and handle preferably making a 65 leak tight fit. At the top and bottom openings of the perforation a reinforce eyelets c are provided, which eyelets have cylindrical shanks which are forced into the opposite ends of the perforation a for a short distance 70 only, and which fit snugly around the handle G. At the outer ends the eyelets have outward shoulders which bear against the outer face of the cork. By this construction the middle portion b of the perforation makes a tight 75 fit with the handle, while the eyelets c give a finished appearance at the top and bottom faces of the cork and serve to reinforce the openings of the perforation.

The handle G and brush H are the usual 80 mucilage brush and handle, consisting of a tubular metal rod flattened at its lower end against a bunch of bristles.

With this construction, owing to the imperfections in the construction of the brush handle, there is a possibility of leakage around the latter in case the bottle is inverted. According to my invention, to avoid this, I coat the under side of the cork, and the lower surface of the handle, and the joint between the 85 cork and the latter, with a thick layer of paraffine or other impervious material, lettered K, which coating continues from the point d near the brush H upwardly and over the bottom face of the cork. This coating prevents 90 all leakage in this direction that might otherwise occur.

To prevent displacement of the handle relatively to the cork I solder the handle at top and bottom of the cork to the eyelets c, there- 95 100

by permanently fixing the parts together, whereby the handle G serves as a permanent handle for the cork. Preferably I continue the coating K entirely across the bottom face 5 of the cork and upwardly over its sides to the point e thereof above the mouth of the bottle, whereby all the surface of the cork and handle which is liable to come in contact with the glue is protected by the paraffine coating. Paraffine and analogous materials are peculiar in that adherents such as glue or mucilage do not act on them, and thus the contents of the bottle, even when the brush H has been scraped over the mouth thereof, 15 do not when the cork is thus covered act to cement the cork to the bottle. On the contrary, any glue scraped on to the neck of the bottle is forced downwardly therein in advance of the cork when the latter is inserted, 20 and thus the mouth of the bottle is always kept free. When thus coated the cork can be inserted and removed with great ease, as its coating acts as a lubricant, permitting it to be slipped into and out of the mouth of 25 the bottle without resistance.

According to one feature of my invention I provide an improved strap for holding the cork in place, the use of which is particularly advantageous when the cork has been coated 30 as described. Preferably this strap consists of a strip of paper I, having an enlarged body portion g, centrally perforated, and having projecting arms or flaps h, of sufficient length to reach over the head C of the bottle and 35 contact with the neck B thereof. The strap I is preferably placed directly on the top face of the cork F and fixed thereon, preferably by the upper eyelet c, the shank of which passes through the perforation in the strap 40 and a flange of which clamps the strap against the top of the cork, whereby it is permanently fastened to the stopper. The flaps h project freely at the sides of the stopper and after the cork has been inserted the ends of the 45 flaps are bent down against, and pasted to, the neck B, thereby binding the stopper in the neck of the bottle and preventing its removal under any ordinary circumstances. Thus the bottle is ready for shipment.

50 The strap I is preferably formed of paper, or of other material which can be easily severed, and when it is desired to open the bottle it is only necessary to cut, tear or break the arms h of the strap at the points i between the bottle and cork, whereupon the stopper can be removed. By reason of the ease with which the flaps of the straps can be broken, the cork can be freed by simply pressing the thumbs against the points i until the 55 fibrous tissue is broken. By reason of the narrow construction of the flaps, the cork and interior of the neck of the bottle are not obscured from view, but can always be inspected before purchase and before the bottle is 60 opened.

It will be seen that my invention provides an improved bottle for glue and like liquids, which is simple, cheap, and can be variously availed of.

It will be understood that the invention is 70 not limited to the precise details of construction shown in Figs. 1 and 2, but that it may be modified in some respects without departing from its essential features.

Fig. 3 illustrates a modification of the invention in which no eyelets are used. In this construction the brush handle, here lettered G', traverses the aperture in the cork, here lettered F', and is inclosed at its upper end in a cap or ornamental handle, lettered L, the 75 base M of which is glued to the top face of the cork. In this construction the perforated paper strap, here lettered I', is slipped over the end of the handle and clamped between the top face of the cork and the bottom face 80 of the base M when these are glued together. The paraffine coating here lettered K' is applied as before described, but in this construction this is not so essential as in the construction previously described, since there is 85 much less risk of leakage around the handle in this instance.

What I claim is, in bottles for glue and like liquids and stoppers therefor, the following-defined novel features and combinations, substantially as hereinbefore set forth, namely—

1. In a stopper for bottles, the cork F, having a central perforation a, in combination with a brush H, having a handle G, traversing said perforation in the cork, and fixed 95 therein, a coating of paraffine K covering the sides and bottom of the cork, the sides of said brush handle beneath the cork, and the joint where said handle enters the perforation in the cork, and a fastening device, as the eyelets c, engaging said handle and said cork and fixing the two rigidly together, whereby there will be no relative movement to break said coating at said joint, and a strap I fixed to the top of said cork, surrounding said handle, and having free ends h, projecting beyond said cork for attachment to the neck of the bottle to retain the cork therein.

2. In a stopper for bottles, the combination with a cork F, having a central perforation a, of a paper strap I, having a perforated middle and free ends, said strap fixed to the top of said cork with the perforation in its middle coinciding with that of the cork, and its free ends projecting for attachment to the 100 neck of the bottle, and a brush H, having a handle G, traversing the perforation through said cork and that through said strap, and projecting above the latter, and means for fixing said brush, strap and cork together, 105 whereby neither can become displaced, substantially as and for the purpose set forth.

3. In a stopper for bottles, the cork F, having a perforation a, in combination with the brush H, having handle G traversing said 110

perforation, the strap I on the upper face of
said cork, and the eyelets *c* surrounding said
handle and soldered thereto, having a shank
entering said perforation *a*, and a flange em-
5 bracing said strap I, whereby said eyelet
clamps said parts together.

In witness whereof I have hereunto signed

my name in the presence of two subscribing
witnesses.
